RECESSING TOOLHOLDER FOR AUTOMATIC MACHINES

Robert C. Zeller and Louis J. Kimpel, Defiance, Ohio, assignors to The Zeller Corporation, Defiance, Ohio, a corporation of Ohio

Application November 28, 1952, Serial No. 322,942

10 Claims. (Cl. 77—3)

1 This invention relates to apparatus for internally recessing sockets in the ends of rotating work-pieces, and is primarily intended for use in automatic multiple spindle indexing chuck machines to perform the internal recessing of a stock piece after it has been subjected to an end boring operation. While the invention is particularly intended for use in connection with a machine of this character, wherein a stock piece is carried by and moved to different working positions by a rotatable indexing turret head, it may be used in a single operation machine where only the internal recessing operation is performed.

The primary object of the invention is the provision in a machine of the class described, of simple, efficient and improved means for positively gauging the depth of internal recessing of a work-piece.

Another object of the invention is the provision of simple and improved means for supporting and controlling the movements of the tool slide holder in connection with a cooperating machine.

Further objects and advantages of the invention will be apparent from the following detailed description, and from the accompanying drawings illustrating one embodiment thereof, in which—

Fig. 1 is a side elevation of an apparatus embodying the invention, with parts broken away and with the recessing tool positioned in a work stock bore and centered with respect to its axis, associated operating parts of the machine being fragmentarily shown;

Fig. 2 is a view looking downward on the recessing apparatus and taken on the line 2—2 in Fig. 1;

Fig. 3 is a cross-section on the line 3—3 in Fig. 1;

Fig. 4 is an end view of such apparatus looking outward on the line 4—4 in Fig. 1, and with a part broken away;

Fig. 5 is a cross-section on the line 5—5 in Fig. 1;

Fig. 6 is a section on the line 6—6 in Fig. 1;

Fig. 7 is a fragmentary section on the line 7—7 in Fig. 1;

Fig. 8 is a section on the line 8—8 in Fig. 1;

Fig. 9 is a perspective view of the tool-carrying bushing;

Fig. 10 is a perspective view of the guide block in which the guide rods of the apparatus are mounted;

Fig. 11 is a perspective view for the tapered gib; and

2 Fig. 12 is a fragmentary view of the work-piece engaging parts in recessing relation.

In automatic screw machines or the like, in connection with which the present recessing means is particularly intended for use, the work stock A (Fig. 1) to be internally recessed is held by a rotatably driven chuck (not shown) that is mounted for revoluble indexing movements to successive working stations by a turret head (also not shown), as well understood in the art. The mounting and control means for the recessing tool 1, and in which the features of the present invention reside, is carried by the customary main tool slide 2 of the machine, as shown in Fig. 1.

In the illustrated embodiment of the invention, particularly as illustrated in Fig. 1, the tool 1 is shown as carried by a head which comprises a slide 4 mounted for reciprocatory sliding movements on a base member 5 transverse to the axis of the tool and, in the present instance, in a vertical plane which intersects at right angles the place of movement of the slide 2. The base member 5 is of rectangular block form and has on its inner or forward side a dovetail 6 receiving a complementary tongue 7 on the adjacent side of the slide 4. One side wall of the groove 6 comprises a longitudinally adjustable tapered gib 8. This gib has an ear 9 at its large end that is notched to receive the shank of an adjusting screw 10 that is held against axial movements by said ear and is threaded into a registering shoulder 11 of the base member 5.

The base member 5, which is generally of rectangular block form, is carried by two guide rods 12, 12 for movements therewith in a plane parallel to the plane of movement of the main slide 2. These rods fixedly project from the rear side of the member 5 and are mounted for longitudinal movements through a guide block 13, in the present instance of cylindrical form, that is clamped to the main slide 2 by a split bearing 14. The rods 12 at the opposite side of the bearing to the member 5 are connected by a cross-piece 15 and from the outer or rear side of this is projected a single rod 16. This rod extends loosely through a spring thrust block 17 that is fixed to the top of the slide 2 in spaced relation to the bearing 14, and its outer end is projected through a stationary frame part 18 of the associated machine for longitudinal movements therein. A stop nut 19 is threaded on the right end for stop engagement with the frame part 18 to limit the extent of inward or forward movement of the tool carrying parts. A coiled compression spring 22 is

mounted on the rod 16 between the cross-piece 15 and the block 17. It is thus apparent that a forward or left movement of the main slide 2 will move the tool carrying unit or head forward therewith to place the tool 1 in work recessing position with the limit of such movement determined by the engagement of the stop nut 19 with the frame part 18. Any movement of the slide 2 beyond the stop position is permitted to take place relative to the tool carrying unit by a yielding of the spring 22. The double rod support for the base member 5 is important in preventing chattering.

The tool slide 4 has a stud 25 near its upper end that projects rearwardly therefrom into the upper end portion of a slot or recess 26 provided in the rear side of the base block 5 and closed at its outer or rear side by a plate 27 removably attached to said block. A coiled compression spring 28 is disposed in said recess 26 and bears at one end sidewise against the stud 25 and at its other end against a shoulder 29 on a tension adjusting screw 30 threaded into the block 5 from an end thereof, as best shown in Figs. 1 and 5. The spring 28 presses the stud 25 against a stop-screw 31 that is threaded in the opposite end of the block. The screw 30 has a stem projecting from its inner end into the spring 28 and normally spaced from the stud 25 and serving to limit its movement from normal position. Each screw 30, 31 is provided with a lock-nut 32.

The tool 1 is mounted in an eccentric bushing 35 in which it is fixed by a set-screw 36 and the bushing is mounted in a socket 37 provided in the outer face of the slide 4 near its inner end. A set-screw 38 secures the bushing in the slide. A rotary adjustment of the bushing in its recess effects a revoluble adjustment of the tool axis. It is apparent that movements of the tool-carrying unit of the main slide 2 moves the tool axially into and out of a work-piece to be internally recessed and that a movement of the slide 4 transverse to the tool axis and against the tension of the spring 28 moves the tool to off-center or recessing position with respect to the work stock. The recessing, of course, occurs when the tool is at the forward limit of its axial movement and is caused by rotation of the work in side wall engagement with the circumferential cutting portion of the tool.

In order that the depth of the recessing may be uniform and of predetermined depth for each work-piece and also for duplicate work-pieces to be subsequently recessed, a work-engaging roll 40 is provided to bear on the outer peripheral surface of the work stock in fixed spaced relation to the tool axis and in the plane of transverse movement of the tool, so as to hold the bore of the work recess concentric with the outside diameter of work.

The roll 40 is carried by the forked inner end of a block 41 in predetermined spaced relation to a side of the tool 1, and this block is mounted on a forward projection 42 of the slide 4. The projection 42 is radially spaced from the tool 1 and may constitute an integral part of the slide 4 or be fixedly attached thereto, as may be desired. The outer side of this projection is provided with a groove radial to the tool axis, and the block 41 is mounted in this groove for adjustment lengthwise thereof. The block 41 is held in adjusted relation to the slide 4 by a clamping screw 43 extending through a longitudinally extending slot 44 therein and threading into said projection. It is thus apparent that the roll 40 is

mounted for radial adjustment relative to the tool 1 and that its carrying block 41 is firmly secured in adjusted relation to the tool slide 4 by the screw 43. The roll 40 is radially spaced from the cutting end of the tool 1 in the plane of movement of said slide on the base member 5 and has rolling coaction with the work periphery in substantially diametrically opposed relation to the tool to limit the depth of recessing by the tool.

10 An adjusting screw 45 for the roll block 41 is threaded endwise in the slide projection 42 and has an annular flange 46 at its head end engaging in a recess 47 in the inner or adjacent side of the block 41.

Automatic machines with which the tool carrying unit embodying the present invention are customarily associated are provided at a side of the stock-carrying parts with a side slide 50 that has a stop pad 51 at its inner end to coact with a stop-screw 52 on a stationary frame part 53 of the machine to limit the extent of inward movement of the slide toward the recessing position of a work-piece A. The slide 50 is provided at its outer side in radial register with the tool-carrying slide 4 with a bracket 54 carrying an adjusting screw 55 the head of which, on an inward movement of the slide, coacts with a stud 56 on the outer end of the tool slide 4 and moves such slide a distance sufficient to offset the tool to have a recessing engagement with the stock wall. This movement of the tool is resisted by the spring 28 acting against the stud 25, so that the cutting pressure of the tool on the work is determined by the spring tension which can be varied by adjustment of the screw 30, and is limited by engagement of the roll 40 with the work stock periphery.

In multiple chuck machines the inward movement of the slide 50 is timed to take place immediately after the tool 1 has been moved axially into the work bore, and the slide dwells in its inward stop position during the resisting period. As the slide 50 recedes, or immediately thereafter, the tool is withdrawn from the work bore 45 by outward movements of the main slide 2.

In the operation of a machine embodying the invention, it will be understood that the main slide 2, with the parts carried thereby, is in outward retracted position during the period of replacing a work-piece in its chuck, or, in the case of an automatic multiple chuck machine, during indexing of the work to recessing position, in which position the work and tool stand in axial alignment. The slide 2 is then moved inward the full length of its stroke and this movement causes the base member 5 and parts carried thereby to move inward until the stop 19 on the rod 16 strikes the frame part 18, after which the spring 22 compresses and compensates for the continued movement of the slide 2. This lost movement action, or the stopping of the inward or forward movement of the member 5, takes place when the tool 1 has been moved forward to proper recessing position in the work stock bore. The inward movement of the side slide 50 now takes place to cause the screw 55 to engage the stud 56 and move the slide 4 with its tool 1 to stock recessing position radially thereof. This position is maintained until the recessing operation has been completed. The roll 40 is properly spaced with relation to the tool axis, so that it will engage and roll circumferentially on the work to limit the permissible depth of recessing.

70 The fine adjustment of the roll block 41 on the slide 4 for this purpose is accomplished by loosening

ing the clamp screw 43 and then turning the screw 45. When the proper adjustment has been obtained, the screw 43 is tightened to fixedly clamp the roll 41 to the slide 4. The centering of the tool axis with respect to the work stock axis, or of the bore therein, is accomplished by adjustment of the screw 31 in the base member 5, as this screw acts against the stud 25 and moves it and the tool carrying slide 4 radially of the work stock axis.

We wish it understood that our invention is not limited to any specific construction, arrangement or form of the parts, as it is capable of numerous modifications and changes without departing from the spirit of the claims.

Having thus described our invention, what we claim as new and desire to secure by United States Letters Patent is:

1. In a machine of the class described, having a rotatable work-piece carrying chuck, a main slide movable in parallel relation to the chuck axis of rotation, the provision of a tool-carrying head, means mounting said head on said main slide for movements therewith and relative thereto in axial relation to the chuck, said head comprising a body member, and a tool-carrying member guided by said body member and movable relative thereto transverse to the chuck axis, a recessing tool carried by said second member for axial movements into and out of the end bore of a work-piece held by the chuck when said head is axially moved and movable lateral to the chuck axis to internally recess the bore of a chuck carried work-piece when said second member is moved relative to the head, means yieldingly retaining said second member with its tool in axial relation to the chuck, a yielding lost motion connection between said head and slide permitting the slide to have a predetermined extent of inward movement relative to the head, and means for limiting the inward movements of the head relative to the slide, and means for imparting predetermined movement to said second member transverse to the tool axis when the head is at the limit of its inward movement.

2. A combination as called for in claim 1, together with means on the tool-carrying member for engaging a side of a work-piece being recessed to limit the depth of recessing and maintaining the recessing operation concentric with the work-piece axis.

3. A combination as called for in claim 2, wherein said last-mentioned means comprises a slide mounted on said tool-carrying member at a side of the tool for adjustment transverse to the tool axis, and a roll on said slide for rolling engagement with the peripheral surface of a work-piece being recessed to limit the depth of recessing by the tool and to maintain the recessing operation concentric with the work-piece axis.

4. In a machine of the class described having a revolvably movable chuck-carrying part with a rotatably driven chuck, and a main slide movable axially of the chuck, the provision of a tool-carrying head including a body member and a slide member carried by the body member and movable relative thereto transverse to the chuck axis, a tool carried by said slide member for movement therewith axially of the chuck into and out of the end bore of a work-piece held by the chuck and also for work recessing movements transverse to the chuck axis, means connecting the slide and body members and acting to yieldingly hold the former with its tool co-

axial with the chuck axis, means at a side of said head operable to move the slide member from normal position relative to the body member to cause an off-center recessing operation of the tool with respect to the work-piece carried by the chuck when said chuck-carrying part is at a predetermined point in its revolvable movement, and lost-motion connection between said main slide and tool-carrying head for imparting predetermined movements from one to the other axially of the chuck.

5. A combination as called for in claim 4, wherein said last-mentioned connection comprises a guide means projecting from the opposite side of said head member to said slide member, means mounting said guide means on said main slide for movement therewith and relative thereto to parallel to the chuck axis, stop means for limiting the inward movements of said guide means and head toward the chuck, and cushion means between said guide means and main slide permitting a predetermined continuation of the inward movement of the main slide after a stopping of the inward movement of said guide means by said stop means.

6. In a machine of the class described, having a rotatable work-piece carrying chuck, the provision of a tool-carrying head, means mounting said head for reciprocatory movements axially of said chuck, said head comprising a body member axially movable relative to the chuck and a tool-carrying member movable with said body member and guided thereby for relative movements transverse to the chuck axis, a recessing tool carried by said second member for axial movements into and out of the end bore of a work-piece held by the chuck when said head is axially moved and is movable laterally to the chuck axis to internally recess the work-piece bore when said second member is moved relative to the head, means normally retaining said second member with its tool in axial relation to the chuck, means for imparting predetermined reciprocatory movements to the head axially of the chuck and permitting it to dwell in recessing position, and means operable to impart predetermined lateral movements to said tool and second member to recess the bore of a work-piece carried by the chuck, said head mounting means including a guide on and movable with the mounting means for imparting reciprocatory movements to the head, and a plurality of laterally spaced guide rods projecting from the head and reciprocably movable in and guided by said guide.

7. In a machine of the class described, having a rotatable work-piece carrying chuck, the provision of a tool-carrying head, means mounting said head for reciprocatory movements axially of said chuck, said head comprising a body member axially movable relative to the chuck and a tool-carrying member movable with said body member and guided thereby for relative movements transverse to the chuck axis, a recessing tool carried by said second member for axial movements into and out of the end bore of a work-piece held by the chuck when said head is axially moved and is movable laterally to the chuck axis to internally recess the work-piece bore when said second member is moved relative to the head, means normally retaining said second member with its tool in axial relation to the chuck, means for imparting predetermined reciprocatory movements to the head axially of the chuck and permitting it to dwell in recessing position, and means at a side of the head operable

to impart predetermined lateral movements to said tool and second member to recess the bore of a work-piece carried by the chuck, said head mounting means including a guide on and movable with the means for imparting reciprocatory movements to the head, guide means projecting from the head and mounted in said guide to guide the movements of the head, means coaxing with said guide means to limit the movement of the head toward the chuck, and a spring connection between said guide means and the means for imparting said axial movements to the head permitting the head to dwell during the predetermined inward movements of said last-mentioned means.

8. In a machine of the class described having a chuck-carrying part with a rotatably driven chuck, and a main slide movable axially of the chuck, the provision of a tool-carrying head including a body member and a slide member carried by the body member and movable relative thereto transverse to the chuck axis, a tool carried by said slide member for movement therewith axially of the chuck into and out of the end bore of a work-piece held by the chuck and also for work recessing movements transverse to the chuck axis, means connecting the slide and body members and acting to yieldingly hold the former with its tool coaxial with the chuck axis, means operable to move the slide member from normal position relative to the body member to cause an off-center recessing operation of the tool with respect to the work-piece carried by the chuck, and connection between said main slide and tool-carrying head for imparting predetermined movements from one to the other axially of the chuck, said last-mentioned connection including a guide fixed on the main slide, a plurality of parallel guide rods projecting from said head member in parallel relation to the movement of said main slide and having longitudinally guided sliding engagement with said guide, together with a cushion connection between said main slide and guide rods permitting predetermined inward stroke movements of the main slide relative to the guide rods, and means stopping the inward movement of the guide rods at a predetermined point in the corresponding movement of the main slide.

9. In a machine of the class described having a revoluble chuck-carrying part with a rotatably

5 driven chuck, and a main slide movable axially of the chuck, the provision of a tool-carrying head, means mounting the head on said main slide for movements therewith and yielding lost motion movements relative thereto, said head including a body member and a slide member mounted on a side of said body member for guided movements transverse to the movements of said main slide, means normally holding said slide member at one end of its said transverse movement, a tool carried by said slide member and normally standing in axial register with said chuck, and means at a side of said head in transversely spaced relation to the tool axis and periodically operable to move said slide member and tool transverse to the chuck axis for side recessing a work-piece carried by the chuck.

10. In a machine of the class described having a revoluble chuck-carrying part with a rotatably driven chuck, and a main slide movable axially of the chuck, the provision of a tool-carrying head, means mounting the head on said main slide for movements therewith and yielding lost motion movements relative thereto, said head including a body member and a slide member mounted on a side of said body member for guided movements transverse to the movements of said main slide, means normally holding said slide member at one end of its said transverse movement, a tool carried by said slide member and normally standing in axial register with said chuck, and means at a side of said head in transversely spaced relation to the tool axis and periodically operable to move said slide member and tool transverse to the chuck axis for side recessing a work-piece carried by the chuck, a block carried by said slide member at its outer side relative to said body member, and a pressure backing roller carried by said block in opposed transversely spaced relation to said tool for side engagement with a work-piece being acted on when the slide member is moved a predetermined extent from normal position relative to the body member.
